UNITED STATES PATENT OFFICE.

NATHAN FRIEDMAN, OF YONKERS, NEW YORK.

SMOKING PIPE.

Application filed February 18, 1928. Serial No. 89,110.

The object of my invention is to provide certain improvements in that type of smoking pipe in which the smoke is cooled and the nicotine is absorbed on its way from 5 the bowl to the mouthpiece.

A further object is to provide certain improvements in the construction, form and arrangement of the several parts of a smoking pipe such as that disclosed by my United 10 States Letters Patent No. 1,443,531, dated January 30th, 1923, whereby the appearance of the pipe is enhanced and its cost of production materially reduced, without impairing its efficiency.

15 A practical embodiment of my invention is represented in the accompanying drawings, in which

Fig. 1 represents the smoking pipe in longitudinal vertical section.

20 Fig. 2 represents a transverse vertical section through the pipe bowl, taken in the plane of the line II—II of Fig. 1, looking in the direction of the arrows.

Fig. 3 represents a detail top plan view of 25 the front end portion of the pipe stem, the front end hollow plug and its absorbent tube being shown partly removed, in dotted lines.

The pipe bowl 1 has the bottom of its 30 tobacco chamber 2 intersected by a transverse pipe stem receiving recess 3, which recess extends from the rear of the bowl nearly to but not through the front of the bowl. This bowl may be made of any desired shape, material and size.

35 The large hollow pipe stem 4 is removably held by friction in the transverse recess 3 and it has a wide slot 5 in its top side wall open through the front end of the stem, which slot forms a hole located in position 40 to open communication between the tobacco chamber 2 and the interior of the pipe stem 4.

The removable mouthpiece 6 has a reduced exterior front end portion 7 which is inserted into the rear end of the pipe stem 4. The front end of the bore 8 through the mouthpiece 6 is enlarged, to removably receive the rear end of a small absorbent tube 9 which extends a distance toward the front 50 end of the pipe stem 4; the said enlarged bore 8 forming an interior annular shoulder 10 for limiting the distance the tube can be inserted into the mouthpiece.

55 The removable metal plug 11 for closing the front end of the pipe stem 4 has a two diameter skirt, the larger portion 12 of

which loosely fits within the bore of the stem and the smaller portion 13 of which is spaced from the inner walls of the stem. The front end of a removable absorbent tube 14 is inserted into the hollow plug 11, which tube extends rearwardly a distance toward the mouthpiece 6. This tube 14 surrounds the tube 9 and is spaced therefrom and from the inner wall of the pipe stem to form a 60 tortuous passage which leads first rearwardly from the tobacco chamber between the stem and outer tube; thence forwardly between the outer and inner tubes, and thence rearwardly through the inner tube to the 65 mouthpiece.

It will be observed that the smaller portion 13 of the skirt of the hollow plug 11 extends rearwardly beyond the hole 5 in the pipe stem to protect the tube 14 from being 70 burned.

It will also be observed that the front end of the pipe stem and its metal plug are entirely housed within the pipe bowl, thus protecting the hand of the pipe user from contact therewith and also preventing any liability of the unintentional removal of the plug from the pipe stem with its outer absorbent tube.

To replace the absorbent tubes, the pipe 85 stem will be removed from the pipe bowl and the front end plug may then be removed with its outer absorbent tube. The absorbent tube may then be removed and another one inserted. Also, the mouthpiece may be 90 removed from the stem with its inner absorbent tube. This inner absorbent tube may then be removed and replaced. The parts may then be reassembled for use.

It is evident that various changes may be 95 resorted to in the construction, form and arrangement of the several parts without departing from the spirit and scope of my invention; hence, I do not intend to be limited to the particular embodiment herein shown 100 and described, but

What I claim is:—

1. A smoking pipe comprising a bowl having a transverse recess intersecting the tobacco chamber and extending partway 105 through the bowl, a hollow stem inserted into said recess and having a hole through its top side wall to open communication between its interior and the tobacco chamber, a removable mouthpiece for the rear end of the stem, 110 a removable hollow metal plug for the front end of the stem, removable inner and outer

absorbent tubes carried by the mouthpiece and plug respectively, to form a tortuous passage from the tobacco chamber to the mouthpiece, the hollow metal plug having a
5 two diameter skirt, the larger portion of which fits within the stem and the smaller portion of which is spaced from the inner wall of the stem.

2. A smoking pipe comprising a bowl having a transverse recess intersecting the tobacco chamber and extending partway through the bowl, a hollow stem inserted into said recess and having a hole through its top side wall to open communication between its
10 interior and the tobacco chamber, a removable mouthpiece for the rear end of the stem,

a removable hollow metal plug for the front end of the stem, removable inner and outer absorbent tubes carried by the mouthpiece and plug respectively, to form a tortuous 20 passage from the tobacco chamber to the mouthpiece, the hollow metal plug having a two diameter skirt, the larger portion of which fits within the stem and the smaller portion of which is spaced from the inner 25 wall of the stem and extends rearwardly beyond the hole in the stem for protecting the outer absorbent tube from being burned.

In testimony, that I claim the foregoing as my invention, I have signed my name this 30
15th day of February, 1926.

NATHAN FRIEDMAN.
